E. P. DUMANOIS,
STARTING APPARATUS FOR INTERNAL COMBUSTION ENGINES,
APPLICATION FILED SEPT. 22, 1919.

1,425,950.

Patented Aug. 15, 1922.

INVENTOR:
Emile Paul Dumanois
By Wm Wallace White
ATTY.

UNITED STATES PATENT OFFICE.

EMILE PAUL DUMANOIS, OF LEVALLOIS-PERRET, FRANCE.

STARTING APPARATUS FOR INTERNAL-COMBUSTION ENGINES.

1,425,950.

Specification of Letters Patent. Patented Aug. 15, 1922.

Application filed September 22, 1919. Serial No. 325,586.

To all whom it may concern:

Be it known that I, EMILE PAUL DUMANOIS, 71 Rue Danton, Levallois-Perret, Seine, France, citizen of the Republic of France, residing at 71 Rue Danton, Levallois-Perret, Seine, France, have invented certain new and useful Improvements in Starting Apparatus for Internal-Combustion Engines, of which the following is a specification.

According to this invention, compressed and carburetted air, that is to say, compressed air mixed with a proper proportion of petrol vapor or other suitable fuel for internal combustion engines, is stored in a container, the storing being effected at any convenient time, but preferably shortly before starting the motor, and the mixture is admitted at the proper moment to the cylinders of the motor to start the same. This may be effected from a distance, if required.

The accompanying drawing, showing an embodiment of the invention, is a sectional view of the apparatus.

The apparatus comprises four main parts: a hand pump designated *a*, a carburetter *b*, a compressed air container, designated *c*, and a fuel container *d*.

It will be understood that these four parts are not necessarily disposed in the relative positions in which they are shown in the drawing: they may be arranged in any other way so as to occupy the least space or to be best adapted to the requirements of the installation. As shown in the drawing, the parts are assembled by means of a bracket *e*, whereby the apparatus can be fixed in a suitable place by means of screws *f*.

The fuel container *d* has an inlet valve *g* for filling it, and at the bottom a valve *h* connected to a pipe *i* leading to the lower part of the carburetter *b*.

The carburetter comprises a closed chamber having an over-flow orifice *j* about midway of its height, and several air-holes *k* at the upper part. A tube *l* depends into the chamber and communicates by means of a passage *m* with a horizontal tube *n*. The latter communicates at one end with the interior of the chamber, and at its other end with a passage leading to a valve *o*. A regulating screw *v* enables the orifice of tube *n* in the chamber to be more or less throttled.

The air pump comprises a barrel with an

air-tight plunger *p* therein, connected by a rod *r* to a handle *s*. At the upper part of the pump there are several air holes *q* which are uncovered by the plunger at the end of its upward stroke. At the lower part there is the valve *o* already referred to, and a valve *t*. The valve *o* admits, under suction, a mixture of atomized fuel and air, and the valve *t* is connected, for delivery, by a pipe *u* to the air container *c*.

The air container *c* has at its upper part a hand valve *x* opening inwards, allowing the contents of the container *c* to flow through a pipe *z*, which supplies the compressed carburetted air to the motor to be started.

A manometer *y* indicates the pressure in the reservoir *c*.

Before starting the motor, and after the container *d* has been filled with fuel, the valve *h* is opened, so that fuel flows to the carburetter chamber, which it fills to the level of the orifice *j*. At the moment when liquid is seen to flow out the valve *h* is closed.

By lifting the handle *s* the plunger *p* is lifted, and produces underneath it a vacuum, so that the valve *o* opens. Air entering the chamber through the holes *k* passes into the tube *n* through the passage left free by the regulating screw *v*, this passage being so regulated that in the tube *n* the pressure is much below atmospheric pressure during the whole of the upward stroke of the plunger. Fuel is thus sucked through the tube *l* and passage *m*, and as the latter and the tube *n* are perpendicular to each other, the currents of air and fuel cross each other and the fuel is atomized.

During the whole of the ascent of the plunger *p* the pump *a* is being charged with a mixture of air and atomized fuel, but at a pressure below atmospheric pressure. At the end of the upstroke of the plunger the holes *q* are uncovered and air from outside immediately enters, re-establishing atmospheric pressure. This additional air gives the carburetted mixture its most efficient composition and assists complete vaporization of the fuel.

The plunger then descends, and during its descent the valve *o* is closed by its spring. The carburetted air is compressed, the valve *t* opens, and the compressed air is forced through the pipe *u* into the container *c*.

A few strokes of the plunger produces in

the container *c* an adequate pressure, read off the manometer *y*. The carburetted air having been thus compressed, all that is required is to press the valve *x*, to admit it 5 to the motor through the pipe *z*.

Having now described my invention what I claim as new and desire to secure by Letters Patent is:

1. A starting apparatus for internal combustion engines, comprising a fuel tank, a carburettor independent from the carburettor of the engine and in communication with said fuel tank, a pump drawing out of said carburettor a mixture of air and 10 atomized fuel and storing and compressing said explosive mixture into a container and means for connecting said container to the explosion cylinder of the engine.

2. A starting apparatus for internal combustion engines comprising a fuel tank, a carburettor independent from the carburettor of the engine and in communication with said fuel tank, means for stopping the flowing of the fuel into the carburettor, 25 a pump, means embodying an inlet valve for connecting the pump to the carburettor, a container for compressed carburettor air, means embodying an outlet valve for connecting the pump to said container, a delivery tube connecting said container to the 30

cylinders of the engine and a discharge valve placed on this tube.

3. A starting apparatus for internal combustion engines comprising a fuel tank, a carburettor in communication with said fuel tank, and provided with an overflow orifice, a pump, means embodying an inlet valve for connecting the pump to the carburettor, a container for compressed carburetted air, means embodying an outlet valve for connecting the pump to the said container and delivery means embodying a discharge valve on said container.

4. A starting apparatus for internal combustion engines comprising a fuel tank, a carburettor in communication with said fuel tank, a pump, means embodying an inlet valve for connecting the pump to the carburettor, a container for compressed carburetted air, means embodying an outlet valve for connecting the pump to the said container, means on the pump for admitting additional air into the same at the end of the suction stroke and delivery means embodying a discharge valve on said container.

In testimony whereof I have signed my name to this specification.

EMILE PAUL DUMANOIS.
